UNITED STATES PATENT OFFICE.

JAMES H. BULLARD, OF SPRINGFIELD, MASSACHUSETTS, ASSIGNOR TO
THE SPRINGFIELD SEWING MACHINE COMPANY, OF SAME PLACE.

FEED MECHANISM FOR SEWING-MACHINES.

SPECIFICATION forming part of Letters Patent No. 249,155, dated November 8, 1881.

Application filed July 28, 1881. (No model.)

To all whom it may concern:

Be it known that I, JAMES H. BULLARD, of Springfield, in the county of Hampden and State of Massachusetts, have invented a new and useful Improvement in Take-Up Mechanisms for Sewing-Machine Feeds, of which the following is a specification and description.

The object of my invention is to provide means for taking up the lost motion occasioned by the wear of the feed-bar in a sewing-machine; and I accomplish this by the means substantially hereinafter described, and illustrated in the accompanying drawings, in which—

Figure I is a reverse plan view of that portion of a sewing-machine bed to which my invention is applied. Fig. II is a plan view of the inside of my adjustable feed-lever cap. Fig. III is a section of the same at line C.

In the drawings, A represents the bed of an ordinary sewing-machine of the class in which the shuttle is moved in a curved raceway by a pivoted shuttle-driver, and in which the feed-bar having the feed attached is moved both horizontally and vertically by a feed-lever provided with an incline, which engages against the lower side of the feed-bar, so that the transverse movement of the engaging end of the feed-lever will move the feed-bar and the feed attached thereto in a direction substantially parallel with the cloth-plate or the bed of the machine, and the longitudinal movements of the feed-lever and the incline made thereon beneath the feed-bar will cause the latter and the feed to rise, this being the ordinary construction of sewing-machines of this class, a spring being usually attached to the bed of the machine and engaging with the feed-bar to move the latter and the feed down.

In the application of my invention to a sewing-machine I may use the same feed-lever as above described, (the construction of which is well known,) and actuated by any suitable mechanism to cause it to give the required horizontal and vertical movements to the feed-bar and feed attached thereto.

1 represents the feed-lever cap, one end of which, on the inside, is provided with projecting guide-flanges, as 4, and that end of the cap

is also provided with an elongated hole through it, as at 2. The flat portion at 20, which is on 50 the upper or inside, forms the seat to support the feed-lever, and upon which the latter moves, and the two grooves, as 6, each side the seat 20, serve to receive any surplus oil and dirt which may work out from between the feed- 55 lever and its seat; and at the end of the cap opposite the elongated hole 2 is made a projection, as 9, against which, when the cap is in place, the pivoted feed-bar 7 rides or bears as it moves both vertically and longitudinally. 60 The outer end of a raised boss, B, on the lower side of the bed, fits nicely between the flanges 4 of the cap 1, and the latter is secured to the boss by a screw, as 3, turned through the elongated hole 2 and into the boss, and the cap is 65 secured in place with the projection 9 close against the feed-bar 7, but just so the latter may move freely between said projection 9 and the bearing 10 cast upon the bed.

If at any time the parts should wear away 70 at these bearings sufficiently to cause lost motion of the feed-bar, the cap 1 may, after loosening the screw 3, be moved up closer to the feed-bar 7, and the screw 3 be tightened again and the lost motion taken up.

As the result in the work of a sewing-machine, as to its appearance, depends largely upon the operation of the feed mechanism, it follows that if the latter is perfect and uniform in its operation the appearance in the stitching when finished will be correspondingly uniform. Hence the importance of preventing any variation in the movement of the different parts of the feed mechanism.

Having thus described my invention, what I 85 claim as new is—

The combination, with the bed of a sewing-machine, of an adjustable cap to support the feed-lever, and provided with a projection to support and serve as a side bearing for the 90 feed-bar, substantially as and for the purpose described.

JAMES H. BULLARD.
